GIRDLE

Patrick J. Morano, Newark, N. J.

Application January 6, 1956, Serial No. 39,642

Term of patent 14 years

(Cl. D20—2)

Figure 1 is a front perspective view of a girdle, showing my new design; and

Figure 2 is a side elevational view of the same.

The dominant feature of my design resides in the combination on the girdle disclosed of the triangularly shaped lower side gussets which slope diagonally to a point at the sides in the plain rear panel in association with horizontally lined upper side panels and the plain front and rear panels, as shown. Hose suspenders are shown by dotted lines for illustrative purposes only.

I claim:

The ornamental design for a girdle, as shown and described.
